DESIGN FOR A CHILD'S BONNET

Marian H. Scherff, Ridgewood, N. J.

Application June 25, 1936, Serial No. 63,484

Term of patent 3½ years

To all whom it may concern:

Be it known that I, Marian H. Scherff, a citizen of the United States, residing at Ridgewood, in the county of Bergen and State of New Jersey, have invented a new, original, and ornamental Design for a Child's Bonnet, of which the following is a specification, reference being had to the accompanying drawing, forming part thereof.

Fig. 2 is a side view of the bonnet shown in Figure 1.

The top and the chin strap of the bonnet, as drawn, are intended to show the knitted surfaces.

The sides of the bonnet, as drawn, are intended to show leather-like surfaces.

I claim:

The ornamental design for a child's bonnet, as shown and described.

MARIAN H. SCHERFF.
